Courtney A. Leubner, Forest Park, Ill., assignor to Supreme Products Corporation, Chicago, Ill., a corporation of Illinois

Filed Apr. 22, 1963, Ser. No. 74,572

Term of patent 14 years

(Cl. D22—3)

FIG. 1 is a perspective view of a housing for a hair clipper showing my new design, the movable and fixed blades being shown in broken lines for illustrative purposes;

FIG. 2 is a top plan view thereof as it appears with the broken line showing of the blade portion omitted for convenience of illustration;

FIG. 3 is a bottom plan view thereof;

FIG. 4 is a side elevational view, the opposite side being the same;

FIG. 5 is a front elevation, viewed from the blade end;

FIG. 6 is a rear elevation;

FIG. 7 is a cross-section to show the exterior aspect taken on the line 7—7 of FIG. 2; and

FIG. 8 is a cross section to show the exterior aspect taken on the line 8—8 of FIG. 2.

I claim:

The ornamental design for a housing for a hair clipper, substantially as shown and described.
